UNITED STATES PATENT OFFICE.

THOMAS A. KEEN, OF NEW ORLEANS, LOUISIANA, ASSIGNOR TO JACOB ISRAEL, OF NEW ORLEANS, LOUISIANA.

GARBAGE-CAN.

1,183,734.

Specification of Letters Patent.

Patented May 16, 1916.

Application filed June 15, 1914. Serial No. 845,262.

To all whom it may concern:

Be it known that I, THOMAS A. KEEN, a citizen of the United States of America, residing at New Orleans, in the parish of 5 Orleans, State of Louisiana, have invented certain new and useful Improvements in Garbage-Cans, of which the following is a specification.

This invention relates to improvements 10 in garbage cans and more particularly to a can of that general type wherein the cover of the can is carried by a bail pivoted to the can body near the bottom thereof and is normally positively held in substantial air-tight sealing engagement with the can in 15 order to prevent or minimize decomposition of the contents of the can, and to prevent the escape of the odors of the garbage.

The object of the present invention is to 20 provide an improved organization of the character stated wherein the can may be readily manipulated to discharge its contents and in such discharging manipulation of the can the cover is released and assumes 25 an open or partly open position, and wherein the cover may be readily opened whenever desired to provide for the deposit of garbage in the can and may be closed and positively locked in closed position.

30 A further object of the invention is to provide a can of the character stated which shall be extremely simple and inexpensive in its structural nature and which withal shall be strong and durable and not liable 35 to derangement by reason of the ordinarily rough or careless usage to which these cans are subjected.

An embodiment of the invention is illustrated in the accompanying drawings, 40 wherein:

Figure 1 is a side elevation of a garbage can in which the features of the invention are incorporated; Fig. 2 is a rear elevation thereof partly in section.

45 Similar characters of reference designate corresponding parts throughout both views.

The can body as 1 is preferably of cylindrical contour and is normally closed by a cover 2 which has a circumferential flange 50 3 to surround the upper end of said can when the cover is closed. The can is carried from place to place by means of a bail 5, the legs of which are pivoted at their lower ends near the bottom of the can as at 6. The

cover 2 is carried by and movable relatively 55 to the bail 5, the connections between said cover and bail comprising pins 7 provided at diametrically opposite points of the cover and slots 8 formed in the side bars of the bail and in which the pins 7 work. The side 60 bars of the bail are provided with pivotally mounted leaf springs 9 having openings 10 near their free ends through which the pins 7 project when the cover is closed. The function of these springs is to positively 65 lock the cover in closed position and they may be readily manipulated to release the cover when the can is to be filled or discharged.

The can body 1 is provided midway between the legs of the bail 5 and near its lower end with a handle 11 by means of which said can body may be tilted when the garbage is to be discharged.

The normal relation of the parts is shown 75 in Fig. 1 and by reference to this figure it will be observed that the bail 5 has an upright position, that the pins 7 are at the lower ends of the slots 8, and are engaged in the openings 10 of the springs 9. The 80 cover 2 thus closes the upper end of the can in a substantially air-tight manner and is positively held in closed position. To discharge the contents of the can the springs 9 are disengaged from the pins 7 and are 85 swung to one side and the cover lifted from the can. Thereupon the can is elevated to a point over the mouth of the receptacle into which the garbage is to be discharged, the bail and the handle of the cover being 90 grasped by one hand and the handle 11 by the other, after which the can is tilted relatively to the bail to discharge its contents. After the contents of the can have been discharged in this manner, the can body is 95 restored to upright position between the legs of the bail and the cover is dropped or forced downwardly upon the can body after which the springs 9 are manipulated to engage the pins 7 and to thereby positively 100 lock the cover in closed position.

When the garbage is to be deposited in the can, the cover is disengaged from the can body in the manner described and the bail 5 is thrown rearwardly and in its rearward movement carries with it the cover. When the cover 2 has been moved rearwardly to a sufficient extent to permit the

deposit of garbage into the can, the bail is restored to its normal position and the cover is closed and fastened as above described.

The garbage can herein described is highly sanitary; it may be readily manipulated either for the deposit of garbage or the discharge of garbage; it may be manufactured at relatively low cost; and it embodies no parts of fragile construction or which are peculiarly liable to breakage or derangement.

Having fully described my invention, I claim:—

15 In a garbage can in combination, a can body, a bail having its legs pivoted at their lower ends at opposite sides of said body,

the pivots being located at fixed points of said legs and of said body, a can cover having a flange to seal the upper end of said body, the bail having longitudinal slots in 20 its legs, pins fixed on said cover for engagement in said slots, and leaf-springs mounted on the side bars of the bail and having apertures through which said pins project in the closed position of the cover.

25

In testimony whereof I have hereunto set my hand in presence of two subscribing witnesses.

THOMAS A. KEEN.
